TOY TRAINING DOLL

Dane B. Coe, Manhattan Beach, Calif., assignor to Innova
Incorporated, Playa Del Rey, Calif.

Filed Dec. 28, 1970, Ser. No. 26,675

Term of patent 14 years

Int. Cl. D21—01

U.S. Cl. D34—4

Fig. 1

Fig. 2

Fig. 3

FIG. 4

FIG. 5

FIG. 1 is a front elevational view of the toy training doll showing my new design;

FIG. 2 is a rear elevational view of the toy training doll shown in FIG. 1;

FIG. 3 is a side elevational view of the toy training doll shown in FIG. 1;

FIG. 4 is a front elevational view of the toy training doll shown in FIG. 1 with outer vest unbuttoned and open, inner vest laced and closed and waistband snapped and overlying the inner vest;

FIG. 5 is a front elevational view of the toy training doll shown in FIG. 1 with the outer vest open, waistband unsnapped and open, inner vest unlaced and open and horizontal zipper extending across the doll's chest.

I claim:

The ornamental design for a toy training doll, substantially as shown and described.
